UNITED STATES PATENT OFFICE

122,975

DESIGN FOR A DRESS ENSEMBLE

Gilberte Andrée, New York, N. Y.

Application September 3, 1940, Serial No. 94,785

Term of patent 3½ years

To all whom it may concern:

Be it known that I, Gilberte Andrée, a citizen of the Republic of France, who have declared my intentions to be a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my design, and

Fig. 2 is a rear view of Fig. 1.

Fig. 3 is a front view of the dress member of the ensemble, and

Fig. 4 is a rear view thereof.

I claim:

The ornamental design for a dress ensemble, substantially as shown.

GILBERTE ANDRÉE.
